[57] CLAIM

The ornamental design for image information reading machine for electronic computer, as shown and described.

DESCRIPTION

FIG. 1 is a top plan view of an image information reading machine for electronic computer showing my new design;

FIG. 2 is a bottom plan view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is an enlarged cross-sectional view thereof as taken from line VII—VII of FIG. 3;

FIG. 8 is an enlarged, cross-sectional view thereof as taken from line VIII—VIII of FIG. 6;

FIG. 9 is a top and left front perspective view thereof on a reduced scale.

FIG. 1

FIG. 2

FIG. 3
